J. VAN VORST.
MOTORIST'S EYE SHIELD.
APPLICATION FILED MAR. 6, 1916.

1,224,431.

Patented May 1, 1917.

UNITED STATES PATENT OFFICE.

JOHN VAN VORST, OF SCOTIA, NEW YORK.

MOTORIST'S EYE-SHIELD.

1,224,431.

Specification of Letters Patent.

Patented May 1, 1917.

Application filed March 6, 1916. Serial No. 12,464.

To all whom it may concern:

Be it known that I, JOHN VAN VORST, a citizen of the United States, residing at Scotia, in the county of Schenectady and State of New York, have invented certain new and useful Improvements in Motorists' Eye-Shields; and I do declare the following to be a full, clear, and exact description of the invention, such as will enable others skilled in the art to which it appertains to make and use the same.

My invention is an improved eye shield for use on automobiles to prevent the glare from the headlights of approaching vehicles from momentarily blinding the operator of the machine to which the device is applied.

The object of the invention is to provide an extremely simple and inexpensive article of the class specified which will be highly efficient and durable, being capable of being immediately adjusted to any position and being so constructed as to cause it to remain in such position.

With the foregoing general object in view, the invention resides in certain novel features of construction and in unique combinations of parts to be hereinafter fully described and claimed, the descriptive matter being supplemented by the accompanying drawing which constitutes a part of this application and in which:

Figure 1 is a side elevation of a portion of an automobile showing the application of the invention thereto;

Fig. 2 is an enlarged side elevation of the device with the attaching clamp partly in section;

Fig. 3 is an edge view of the upper portion thereof;

Fig. 4 is an enlarged vertical section taken on the plane of the line 4—4 of Fig. 2;

Fig. 5 is a plan view of the partially completed clamp.

In specifically describing the construction shown in the drawing above briefly described, similar characters will be placed on corresponding parts throughout the several views, and reference will be herein made to the numerous elements by their respective indicies. To this end, the numeral 1 represents a pliable tube carrying at one end a partly transparent eye shielding plate 2 preferably of amber colored celluloid, while at its other end said tube is provided with a clamp 3 for securing this end to the steering post 4 of an automobile, the plate 2 be-

ing adapted to be swung into the operator's line of vision to shield his eyes from the glare of the headlights of approaching machines.

The tube 1 is formed of a single strip of metal 5, this strip being S-shaped in cross section and being coiled as shown, with the curls at the edges of the numerous convolutions interengaging such curls on the adjacent convolutions. Certain of these curls constitute an internal shoulder 6 which serves as a screw thread in a manner to be hereinafter set forth.

A clamp 7 is provided for securing the plate 2 to the tube 1, this clamp being formed of a single strip of appropriate metal 8 having on its ends flat jaw plates 9 (see more particularly Fig. 5). The central portion of the strip 8 is preferably in the form of a disk 10 as shown, this formation being attained by suitably notching the edges of said strip. With the exception of the disk 10, the strip 8 is stamped into semi-tubular shape, the inner portions of the plates 9 being also shaped in this manner to reinforce said plates. Screw threads 11 are stamped on the strip 8 between the disk 10 and the jaw plates 9 as shown. The general outline shown in Fig. 5, and the stamping operations described may all be attained at a single operation by appropriate dies, thus rendering the clamp extremely easy to manufacture. After completing the formation described, the strip 8 is folded substantially upon itself to bring the jaw plates 9 into parallel relation and at the same time to form a split attaching plug or shank 12 for said jaws the inner end of this shank being formed by the disk-like formation 10, said end being of less diameter than the outer end of the shank.

The shank 12 is threaded into the upper end of the pliable tube 1, with its screw threads 11 frictionally engaging the thread 100 or shoulder 6 within said tube; and the eye shielding plate 2 is clamped between the jaw plates 9, these plates being forced into binding contact with said plate 2 by the tapered formation of the shank 12. The frictional contact existing between the shoulder 6 and the threads 11 is such as to tend to contract the convolutions of the strip 5 when an attempt is made to remove the clamp by turning it in a retrograde direction. The result of this is that the aforesaid convolutions will contract around said shank

and will thus positively hold it against removal by turning in the direction mentioned.

In order to remove the clamp should it be desirable for any reason, it is first necessary to expand the convolutions at the upper end of the tube 1, and for this purpose one edge of the plates 9 at the juncture of this edge with the shank is so shaped as to cause it to serve as a tube expanding cam 13. This is accomplished by disposing said edge at a very obtuse angle to the shank, whereby if the clamp be turned further in the direction in which it must be moved to apply it to the tube 1, the cam 13 will be drawn into the upper end of said tube. The result of this is that the convolutions at this end of the tube will be expanded and will thus disengage the shoulder 6 from the screw threads 11. Simultaneously with this releasing, the shank 12 will move outwardly a distance approximately equal to the width of one of the threads 11. When the plug is in this position, due to its tapered formation, there will be no noticeable amount of friction existing between it and the tube, and consequently it may be rotated in the reverse direction and removed. The upper end of the tube 1 is preferably disposed obliquely as shown at 18 in order that the cam 13 may operate more quickly than would otherwise be possible.

The clamp 3 above referred to is preferably in the form of a split collar having overlapped ends, the innermost of these ends having a threaded opening 14 while the outer end is formed with a circumferentially spaced series of unthreaded openings 15. In applying the device, the collar is expanded and passed around the steering post 4, after which a screw 16 is passed through the appropriate opening 15 and threaded through the opening 14 into contact with said post. This type of clamp will be very efficient regardless of its extreme simplicity.

By constructing the entire device in the manner above described, it may be easily and inexpensively manufactured and marketed and when applied to use, will be a very easily operated and effective article. Due to the structure of the tube 1, it is pliable in all directions and may thus be quickly and easily moved to position the plate 2 in the driver's line of vision. This may be accomplished without moving either hand to a point remote from the steering wheel as will be obvious from an inspection of Fig. 1.

I claim:

1. An eye shield of the class described comprising a pliable tube formed of a coiled strip of metal and having an internal shoulder following the convolutions of said coiled strip, a tapered plug received in one end of said tube and having external screw

threads engaging said shoulder, said plug being split longitudinally into two parts whose outer ends extend beyond the tube and are fashioned into a pair of jaws, and a partially transparent plate having one edge gripped between said jaws. 70

2. An eye shield of the class described comprising a pliable tube formed of a coiled strip of metal and having an internal shoulder following the convolutions of 75 said strip, a plug in one end of said tube having external screw threads frictionally contacting with said shoulder, such friction serving to contract the convolutions of the coil when an attempt is made to remove the plug by turning the same in a retrograde direction, thereby holding said plug against rotation in this direction, and a partly transparent plate carried by the plug. 80

3. An eye shield of the class described comprising a pliable tube formed of a coiled strip of metal and having an internal shoulder following the convolutions of 85 said strip, a plug in one end of said tube having external screw threads frictionally contacting with said shoulder, such friction serving to contract the convolutions of the coil when an attempt is made to remove the plug by turning the same in a retrograde 90 direction, thereby holding said plug against rotation in this direction, a cam for expanding the convolutions of the tube when the plug is turned in the opposite direction, thus releasing the shoulder from engagement 100 with the screw threads, and a partly transparent plate carried by said plug. 105

4. An eye shield of the class described comprising a pliable tube formed of a coiled strip of metal and having an internal shoulder following the convolutions of 110 said strip, a plug in one end of said tube having external screw threads frictionally contacting with said shoulder, such friction serving to contract the convolutions of the coil when an attempt is made to remove the plug by turning the same in a retrograde direction, thereby holding said plug against rotation in this direction, a cam, carried by the plug for expanding the convolutions of the tube when said plug is turned in the opposite direction, thus releasing the shoulder from engagement with the screw threads, and a partly transparent plate carried by said plug. 115

5. An eye shield of the class described comprising a tube having an internal screw thread at one end, a partially transparent eye shielding plate, and a clamp for securing said plate to the tube, said clamp 125 comprising a pair of stamped metal semi-tubular members having external screw threads stamped thereon and serving to form a tapered attaching shank which is threaded in said end of the tube, the outer 130

ends of the aforesaid members having thereon flat jaw plates between which the aforesaid eye shielding plate is gripped.

6. An eye shield of the class described comprising a tube having an internal screw thread at one end, a partly transparent eye shielding plate, and a clamp for securing the plate and tube together, said clamp being formed of a single strip of metal having at its ends flat jaw plates, the strip and part of said plates being stamped into semi-tubular shape, and the strip having screw threads stamped thereon, said strip being then bent substantially upon itself to dis-
10 pose the jaw plates in parallel relation and at the same time to provide a split tapering attaching shank for said plates, said shank being threaded into the tube and said eye shielding plate being clamped between said
15 jaw plates.

7. A clamp for securing eye shields to

the steering posts of automobiles, said clamp being formed of a single strip of metal bent into the form of a collar with overlapped ends, the inner end having a 25 threaded opening while the outer end is formed with a series of circumferentially spaced openings, said collar being adapted to be passed around the aforesaid steering post, and a clamping screw for passage 30 through any one of the series of openings and to be then threaded through said threaded opening and into contact with said steering post.

In testimony whereof I have hereunto 35 set my hand in presence of two subscribing witnesses.

JOHN VAN VORST.
